(No Model.)

P. F. KING.

NAIL EXTRACTOR.

No. 339,993.

Patented Apr. 13, 1886.

UNITED STATES PATENT OFFICE.

PHINEAS F. KING, OF KANSAS CITY, MISSOURI.

NAIL-EXTRACTOR.

SPECIFICATION forming part of Letters Patent No. 339,993, dated April 13, 1886.

Application filed January 18, 1886. Serial No. 188,929. (No model.)

To all whom it may concern:

Be it known that I, PHINEAS F. KING, of Kansas City, in Jackson county and State of Missouri, have invented a certain new and useful Improvement in Nail-Extractors, of which the following is a full, clear, and exact description, reference being had to the accompanying drawings, forming part of this specification, and in which--

10 Figure 1 is a perspective view of the tool. Figs. 2, 3, and 4 are detail side views illustrating the manner of using the tool, and Fig. 5 is a similar view showing another way in which the tool may be used.

15 A is the stem or lever-bar, which may be properly made of wrought or malleable iron. B is the handle.

C is a shoe, slotted at c, to allow the passage of the bar A, and supported on a pivot-bolt, 20 D, passing through the sides of the shoe and through the lever-bar A. The length of the slot c is sufficient to allow the lever A a limited movement on the pivot D. The movement of the lever is limited in the shoe, to prevent the pulling-jaws coming in actual contact, and to enable the lever and the curved fulcrum-bar c' to act together as a bell-crank lever in the drawing of the nail from the wood. The other arm, c'', of the shoe is slotted or mortised 25 for the passage of the shank E of the jaw E'. This shank is held in position in the mortise by a set-screw, F.

E' is a ball on the end of the shank, said ball being of a size to form a good grip for the hand.

30 The jaw E' has a chisel-edge, e, which is fitted to cut a groove in the wood, and to engage the nail G beneath the head, as seen in Figs. 3, 4, and 5.

H is a set, which is fixed in a mortise or 40 socket made in the end of the bar A. This set forms one of the gripping-jaws. It may be held in by the pivot-bolt D. The construction is such that the set may be replaced by another or may be removed for repointing.

45 The position of the tool when first applied to the nail is shown in Fig. 2, where I represents the wood in section. One hand is applied to the handle B of the bar A, and the other to the ball E' of the jaw E'. Then, without materially moving the lever-bar A, the shank E of jaw E' is moved in the direction

shown by the arrow, which plows a channel, i, in the wood, and forces the jaw E' against the nail below the head, as seen in Fig. 3. The lever-bar A is now moved in the direction indicated by the arrow, which first forces the jaw H into the wood, and then lifts both jaws, with the nail, by bearing on the curved arm c as a fulcrum. (See Fig. 4.) The form of the arm c is such that the nail is drawn out- 55 6c ward in almost a straight line.

In drawing the lighter class of nails, especially those having heads, the hand may be removed from the ball as soon as the jaw E' has come in contact with the nail, as the weight 65 of the ball is sufficient to maintain the hold of the jaw upon the nail.

When the tool is operated as shown in Fig. 5, the chisel-jaw E' is first placed through the wood into engagement with the nail, and then, 70 the lever-bar A being moved in the direction of the arrow, the jaw H is first brought into engagement with the nail, as seen in Fig. 3, and then the nail drawn out. (See Fig. 4.) The end h of the set H is rounded, so as to give a 75 curved cutting-edge, h', as seen in Fig. 1, so as to prevent the jaw from slipping transversely from the nail. The same object would be accomplished by making the edge angular.

I have shown the shoe C as pivoted to the 80 lever A; but this, though my preferred construction, is not absolutely essential, as the fulcrum bar or arm c might be rigidly attached to the lever A, the jaw E' being hinged to the lever to operate substantially as set forth. 85

In the practical use of the tool the wood shaving comes between the jaw E' and the nail, and prevents the wear upon the edge of the jaw.

It will be understood that no concussion of 90 any kind is used in operating the tool, so that there is neither noise nor jar.

It will be seen that there is no spring in the tool to get out of order.

The shank E, I have made of ordinary bar- 95 steel pointed up, as shown at E', and as the point wears the shank can be set down to compensate for the wear.

In adjusting the jaw E' for work it is so placed as to cut into the wood the required 100 depth. While the jaw H is resting on the surface of the wood, then as the lever A is swung

over on the fulcrum the jaw H is drawn down into the wood by the bearing of the jaw E' upon the nail.

I claim as my invention—

- 5 1. The combination of the lever A, with removable jaw or set H, the fulcrum-shoe C, pivoted to the lever having a curved fulcrum-arm, c, and a projection, c', in which is held the weighted shank E of the jaw E', substantially as and for the purpose set forth.
- 10 2. The combination of lever A, with jaw H secured in its end, fulcrum-shoe C, pivoted to the lever having a curved fulcrum-arm, c, and a projection, c', mortised to receive the shank

E of the jaw E', said shank being adjustable in 15 the mortise and secured by set-screw therein.

3. The combination of lever A, with jaw H secured in its end, fulcrum-shoe C, pivoted to the lever having a curved fulcrum-arm, c, and a projection, c', mortised to receive the shank 20 E of the jaw E', said shank having a weight or ball, E', upon it, and being adjustable in the mortise and secured by set-screw therein.

PHINEAS F. KING.
